UNITED STATES PATENT OFFICE.

GEORGE W. MANLEY, OF RANTOUL, ILLINOIS.

LANTERN.

SPECIFICATION forming part of Letters Patent No. 728,738, dated May 19, 1903.

Application filed November 8, 1902. Serial No. 130,608. (No model.)

To all whom it may concern:

Be it known that I, GEORGE W. MANLEY, a citizen of the United States, residing at Rantoul, in the county of Champaign and State of Illinois, have invented new and useful Improvements in Lanterns, of which the following is a specification.

My invention has relation to improvements in lanterns of that kind or class adapted for railway signaling; and the object is to provide a lamp or lantern of the kind named and for the purposes stated whereby a "clear" signal may be changed to indicate another character of signal—such as "danger," "caution," and other designated or determined character prescribed by the rules of the road—and then restored as desired to the original or primary condition.

The invention embodies a lantern comprising the usual constructions and equipments, a base-ring, a lifting expanding spring, and a colored cylinder seated on the ring and adapted to be depressed and elevated, all as will be fully set forth and the novelty claimed particularly and distinctly pointed out.

I have fully and clearly illustrated my invention in the accompanying drawings, forming a part of this specification and wherein—

Figure 1 is a side elevation of a lantern equipped with my improvements, showing the colored signal-cylinder elevated. Fig. 2 is a horizontal section taken on the line 2 2 of Fig. 1, showing the arrangement of the parts. Fig. 3 is a central vertical section through the lantern, showing the aggroupment of the parts, with the lifting-spring expanded and the colored signal-cylinder in elevated position surrounding the lamp-flame. Fig. 4 is a perspective view of the colored signal-cylinder. Fig. 5 is a perspective view of the supporting-ring on which the colored signal-cylinder seats.

In the drawings similar reference notations designate like parts in all of the illustrations.

Referring to the drawings, A designates the lantern-frame, comprising vertically-arranged standards 1 in radial relation and formed with inwardly-extending knees 2. These standards are connected and strengthened above the knees by wires 3, passed through them with the ends cemented together, and at the base is a similar wire 4,

which strengthens and binds the legs together. At the top of the standards is secured a flanged ring 5, to which is hinged the cover 6, formed with a flue extension 7, perforated as usual to provide a draft for the lamp. A spreader 8 is located in the flue extension. A snap-catch 9 is secured to the cover 6, which engages the flange on the ring 5 and locks the cover in closed position. Between the knees 2 is arranged and secured the lamp-cylinder 10. This consists of a metal cylinder having open ends and of such height and diameter as may adapt it to receive and contain the lamp and to hold the base-flange of the chimney 11, the top of which is held in place by a circular flange 12 on the inner face of the cover. 13 designates the lamp of the usual make, having its bottom extended and formed with a vertical annular flange 14, which fits up around the lower part of the cylinder 10 and is detachably held in position by the engagement of laterally-projecting lugs 15 on the cylinder with a slot 16 and a spring-tongue 17 in a well-known manner. A carrying-bail 18 is secured to the upper ends of opposite standards, as shown. Each and all of these elements and parts heretofore described are of well-known construction, except that the lamp-cylinder 10 is preferably made longer than usual to fully accommodate the improved appliances and parts involved in my invention, and also certain changes are made in the cylinder 10 for the same purpose, and these, with the other embodied parts of the invention, I now proceed to describe.

19 designates an expansive spiral spring disposed in the space between the cylinder 10 and the lamp 13, as shown in Fig. 3 of the drawings, with the lower coil secured in clips 20 in the inner face of the cylinder 10 and having its upper coil secured to a circular plate-ring 21 by eyes or clips 22. The ring 21 constitutes the support for the colored signal-cylinder and is formed with upwardly-extended and inwardly-directed ears 23, which engage over the skirt-flange 24 of the colored signal-cylinder 25. Diametrically opposite to each other on the ring 21 are formed finger-pieces 26, which slidably engage in vertical slots 27 28 in the cylinder 10 and lock in the bayonet extension 29 of the

slots, so as to hold the spring depressed and the colored cylinder down in its lower position. The colored signal-cylinder, as heretofore mentioned, may be of any selected 5 color designed to publish a signal having a prescribed meaning.

The utilization of the improvements may be stated as follows: Normally the white light is displayed and indicates a well-known 10 signal; but should a signal of other significance and meaning be required then a lamp having a colored cylinder of the kind necessary is selected, the arms 26 are unlocked, and the spring moves the colored cylinder 15 into upper position and surrounding the white light, and a signal of the selected color is displayed. When the exigency has passed, the spring is depressed, carrying with it the colored cylinder, and again the white light 20 prevails.

The advantages attending the use of a lantern of the construction specified are several and important. Every trainman, switchman, flagman, or other employee of a railway company 25 whose duties require him to attend on the coming and going of trains is under present régime provided with a red lantern or any other color indicative of danger or caution and at the same time is allowed to carry

only one lantern, the signal designation of 30 which is stationary and unchangeable, while in the instance of the invention he carries a lantern which can be changed to impart either a clear signal or a danger indication. Its use also materially reduces the expense in the 35 stock of lanterns and saves in cost of oil and labor of keeping the lanterns supplied.

Having thus fully described the invention, what is claimed as new is—

In a signal-lantern, the combination with 40 the lamp, having its bottom extended and formed with a vertical annular flange, of a lamp-cylinder formed with opposite vertical slots having bayonet extensions at their base, an expansive spring arranged between the 45 lamp and the lamp-cylinder, a plate-ring secured to the upper coil of the ring formed with diametrically opposite finger-pieces to slidingly engage in the vertical slots of the lamp-cylinder, and a colored signal-cylinder 50 mounted on the ring.

In testimony whereof I affix my signature in presence of two witnesses.

GEORGE W. MANLEY.
